PRINTING MECHANISM

Morris J. Hoffman, Chicago, Ill.

Application December 5, 1936, Serial No. 114,419

12 Claims. (Cl. 101—93)

This invention relates to printing mechanism and in its present form it has been designed to print data of various kinds on coupon tickets, such as are used for keeping record of workmen's time on wearing apparel or other articles of manufacture.

Ordinarily coupon tickets comprise two spaced rows of coupons which are detachable from the remainder of the ticket, and each coupon bears data concerning the work done by the workmen upon the goods. Sometimes the data consists of the lot or job number, the price paid to the several workmen for labor performed upon the articles and the names of the particular operations performed.

One of the objects of the present invention is to provide mechanism, by means of which all of the data may be printed upon a coupon ticket in one operation. Sometimes one and the same identification number is printed upon each of the coupons of the ticket, and other dissimilar data is printed upon the coupons, and one of the objects of the present invention is to provide means whereby all of the printing elements which print the numbers may be set up by a simple operation, and the remainder of the data may be set up or applied to a slide which may be placed in a slightly higher plane than the other type faces, together with means for making an impression of all of the type faces in one operation.

With these and other objects and advantages in view, this invention consists in the several novel features hereinafter fully set forth and claimed.

One embodiment of the invention is illustrated in the accompanying drawings, in which:—

Fig. 1 is a plan of the printing mechanism with certain portions broken away and other parts omitted for the purpose of clarity;

Fig. 2 is a vertical cross-section, taken on the line 2—2 of Fig. 1;

Fig. 3 is a fragmental, vertical, longitudinal section, taken on the line 3—3 of Fig. 1;

Fig. 4 is a fragmental, perspective view of certain liners used for supporting and guiding the type bars, the guide member and the slide used;

Fig. 5 is a plan of one of the type strips used on the slide, seen in Fig. 4;

Fig. 6 is a fragmental plan of one of the printed coupon tickets and an adjacent unprinted one; and

Fig. 7 is a plan of one of the type bars used in the device.

Referring to said drawings, the reference character 10 designates a hollow rectangular base, in

which the type mechanism is contained, and 11 designates a cover which is hinged to the base by hinges 12 and is arranged to be locked or otherwise secured thereto by pins or other locking means 13.

Within and extending transversely of the base, are a multiplicity of spaced liners 14, which are spaced apart by washers 15 (see Fig. 2) and tied together by rods 17 extending through the liners and washers and having nuts 16 threaded upon their outer ends for clamping the parts together. The liners are supported by cross bars 18 which are fastened upon the ends of the liners by rods 19 having nuts upon their ends that bear against the bars, and the entire structure described is rigidly fastened in the base. The liners 14 are arranged in groups, and the liners 14^a, which divide the liners 14 into groups, have upward extensions 14^b, the purpose of which will be hereinafter explained.

Slidably resting upon the liners 14 are type bars 20, which have spaced duplicate sets of type faces 21 upon their upper edges adjacent their ends, as seen in Fig. 7, said type faces desirably comprising the digits 0 and 1 to 9 and other characters, if desired. When the type bars are in neutral position, as seen in Figs. 1 and 2, all of the corresponding type faces on the type bars are aligned with other, but the type bars may be adjusted from said neutral position to a printing position, in which the type faces that are in printing position co-operate with impression making means to print the members or characters set up.

It is to be understood that when the type bars are set into printing position, two rows of type faces are set into printing position to print upon two rows of spaced coupons. The printing position of the type faces, namely, the lines in which the type faces print, is indicated by the arrows, a, in Figs. 1 and 2. Six type bars are shown in each group so that each group is capable of printing a selected number composed of six digits on two spaced rows of coupons.

Suitable means are provided for simultaneously setting up the corresponding type bars of the several groups into printing position and the means here shown comprise shafts 22, one for each type bar of a group, said shafts being rotatively mounted in the base and liners and having pinions 23 rigidly mounted thereon and arranged to mesh with rack teeth 24 provided upon the lower edges of the type bars. The several pinions on each shaft mesh with the several correspondingly located type bars of all of the groups. Upon the outer ends of the shafts 22

are knobs 24, by means of which the shafts may be manipulated to set the type bars into printing position. For indicating the type faces at the printing position, a group of indicating bars 5 25, similar to the type bars, are provided at one end of the machine and said indicating bars mesh with pinions 25^a upon the shafts 22 in the same manner as the type bars 20. The upper edges of the indicating bars 25 are provided 10 with indicating characters corresponding with those on the type bars, and said indicating characters are visible through a window 26 in the cover 11 when the bars are adjusted.

By observing the type characters as they appear 15 through the window, the attendant turns the various shafts 22 until the proper characters appear. The type bar setting mechanism above described exemplifies one form of setting mechanism, but it is to be understood that various 20 equivalent means may be provided for setting the printing bars into printing position. A fuller description of type bars and setting mechanism therefor is more fully shown and described in Letters Patent No. 1,371,893, issued to me March 25 15, 1921.

Two rows of figures, b, are printed with the type bars upon the two rows of coupons, c, of a coupon ticket C, a fragment of which is seen 30 in Fig. 6. The coupons are separated from the middle portion, c¹, of the ticket and, if desired, the ticket may be scored or perforated along the adjoining margins of the coupons whereby they 35 may be readily torn from the remainder of the ticket. However, this is not essential to the invention as the score lines or perforations may be omitted if so desired and the coupons may be clipped from the ticket.

For printing other data upon the several coupons, such as the prices paid the workmen for 40 performing work on wearing apparel or other articles represented by the coupon ticket, and for printing data such as the names of the several operations on the articles, auxiliary printing means is provided, which is disposed directly 45 above the type bars in position to print upon the coupon ticket during the operation of printing the rows of figures, b, thereon, said auxiliary printing means will now be described.

Extending longitudinally of the base and secured to and supported by the raised portions 50 14^b of the liners 14^a, is a flat guide member 27 provided with inturned side flanges 28 which provide oppositely disposed grooves for guiding a type carrying slide 29. An upturned flange 27^a 55 at the end of the guide member provides a stop for the slide to position the same in a device. The bottom of the guide member 27 is placed immediately above the type faces on the type bars, whereby the bars may slide freely underneath the guide member in adjusting the type bars into printing position.

The slide 29 is provided with means for removably supporting a number of type strips 30, that are provided with type faces 31 at both 60 ends, adapted to print in spaced rows upon the coupons adjacent the ends thereof which are attached to the middle portion, c¹, of the ticket. Conveniently, the slide 29 is provided with transversely extending inturned lips 32, 33 that provide 65 grooves in which the strips may be inserted in attaching them to the slide. The lips 32, 33 are disposed above and in line with the liners 14^a which support the guide member 27, whereby the type strips may be located directly above 70 the groups of type bars, as seen in Figs. 1 and 3.

I have shown one type strip 30 for each group of type bars, adapted to print data in connection with the numbers printed by the type bars. If desired, the type strips may be in the form of two pieces, one disposed adjacent each side edge 5 of the slide. The type faces 31 are formed upon the type strip in any well known manner, and desirably two rows of type faces are provided adjacent each end of each type strip, whereby to print two kinds of data upon each coupon, 10 as for instance, the prices paid the several workmen for performing the operations upon the article which prices are indicated at d, in Fig. 6, and the names of the operations performed by the workmen on the article as seen at e. 15

A large assortment of type strips is furnished with each printing device, as this enables the user of the machine to print a great number of combinations of prices and names of operations along with the numbers that are printed on the 20 coupons. The prices for the several operations may vary in accordance with the character or quality of the articles with which the coupon tickets are used, and with the use of removable and interchangeable type strips any desired combination may be obtained. Furthermore, several slides may accompany the device, and the usual combinations of prices and operations may be set up in the several slides thereof, and when it becomes necessary to change some particular price 25 or prices for a certain order all that is necessary for the attendant to do is to select type strips for printing the proper data and insert them in place of the others.

An inked ribbon 34 overlies the type bars and 35 auxiliary printing means and may be wound upon spools 35 supported by the cover 11 on the underside at the front and back thereof.

As a preference a roll 36, composed of a wide strip of light cardboard or heavy paper, is used 40 for making the tickets, and the cardboard or paper may be scored transversely as at c² in Fig. 6 to separate the tickets C from each other. The roll is carried by brackets 37 mounted on the rear of the base and the end of the ticket strip 45 36^a thereof is fed through a slot at the rear of the base and over the inked ribbon to the front of the machine, where its extreme end protrudes through a slot 38 in the cover in position to be taken hold of and drawn out of the device. 50

Any suitable impression making means may be provided in connection with the type bars and auxiliary printing means and, as seen, said impression making means is contained in a housing 39 which rises from the plate 40 of the cover 11. 55 Two narrow impression rollers 41 co-operate with the type faces 21, which are in printing position, to make impressions on the coupons, and an impression roller 42, located between the rollers 41, is provided for making impressions from the 60 type faces 31 on the auxiliary printing means. The rollers are journaled in brackets carried by a slide roller supporting member 43 which is slidably guided in the side walls 44 of the housing, and has a knob 45 extending through a slot 65 in the top wall of the housing that provides means for moving the roller supporting member 43 and therewith the rollers across the coupon ticket to make the impressions thereon.

Desirably the impression roller 42 is yieldably 70 supported in its brackets and for this purpose springs 46 are provided in the brackets which bear against the bearings for the roller and permit the roller to yield upwardly when traveling over the auxiliary printing means. 75

When a roll of cardboard or paper is used, the tickets are detached after being printed, and it is desirable to provide means to facilitate tearing a printed ticket from the remainder of the ticket strip. The means shown comprise a strip tearing bar 45 disposed above the plate 40 of the cover 11 and directly in front of the housing 39, the lower edge of which may be pressed down on the ticket strip at the row of perforations c^2 between the printed ticket, which has now been withdrawn, and the next adjacent unprinted ticket. The strip tearing bar 45 is guided in posts 47 adjacent the side edges of the plate 40 and said bar is urged upwardly by coiled compression springs 48 contained in the posts and bearing against the underside of the bar. A knob 49 may be employed on the bar to facilitate pressing it down on the ticket strip. It is to be understood that the printed ticket is withdrawn far enough to bring the row of perforations between it and the next adjacent ticket beneath the strip tearing bar, the bar pressed down on the ticket strip and the printed ticket torn off along the edge of the strip tearing bar.

For guiding the ticket strip over the type bars and auxiliary printing means, rods 50 (see Fig. 2) may be provided above and below the ticket strip, between the middle and end rollers.

In use the end of the ticket strip is threaded through the device above the inked ribbon to the strip tearing bar. The slide, with the selected type strips attached thereto, is inserted in the guide member, thereby bringing the several type strips over the groups of type bars. The type bars are then adjusted to bring the selected type characters into printing position to print the selected number on the coupons. The impression making device is then moved across the ticket underneath it. The rollers 41 press the ticket against the ribbon over the type faces of the type bars that are in printing position and the roller 42 presses the ticket upon the ribbon over the type faces on the slide, thereby printing all of the data on the ticket in one operation. After the ticket has been printed, it is withdrawn and torn from the remainder of the ticket strip, as has been explained.

With the present printing mechanism, the ticket strip need have no data previously printed on it, which is a great saving in the cost of the strip and, inasmuch as all of the data on a ticket may be printed in one operation, time and labor are saved and there is less likelihood for mistakes.

More or less variation of the exact details of construction is possible without departing from the spirit of this invention. I desire, therefore, not to limit myself to the exact form of the construction shown and described, but intend, in the following claims, to point out all of the invention disclosed herein.

I claim as new and desire to secure by Letters Patent:

1. In printing mechanism, the combination of a base, type bars arranged side by side in groups and slidably mounted in the base, means to actuate said type bars whereby to set selected ones in printing position, auxiliary printing means comprising a guide member supported above the type bars in close proximity thereto, and a slide having type faces thereon and slidably held on said guide member, and impression making means co-operating with said type bars and auxiliary printing means to make impressions thereof.

2. In printing mechanism, the combination of a base, type bars arranged side by side in groups,

and slidably mounted in said base, all of said type bars having type faces thereon, in duplicate, at both ends of the bars, type setting means for setting similar selected type faces of the several groups into printing position in two spaced lines, 5 a guide member extending transversely of the type bars, supported thereabove in close proximity thereto, a slide removably supported by said guide member in a plane slightly above the plane of the type faces on the type bars, type faces on said 10 slide, and impression making means co-operating with the type faces that are in printing position to make impressions thereof.

3. Printing mechanism, comprising in combination, a base, type bars arranged side by side in groups and slidably mounted in said base, said type bars having type faces thereon adjacent each end, setting means whereby to set selected type faces in two spaced rows, and whereby to print on two rows of spaced coupon tickets, auxiliary 15 printing means disposed slightly above the type bars and located between the printing position of the type bars, said auxiliary printing means having interchangeable type faces located thereon adjacent the printing position of the type 20 bars, whereby to print data on said coupons, and impression making means co-operating with the type faces to make impressions thereof.

4. Printing mechanism, comprising in combination, a base, type bars arranged side by side in groups and slidably mounted in said base, said type bars having type faces thereon adjacent each end, setting means whereby to set selected type faces in two spaced rows, and whereby to print on two rows of spaced coupon tickets, auxiliary 30 printing means disposed slightly above the type bars and located between the printing position of the type bars, said auxiliary printing means having a removable slide and interchangeable type strips 35 removably carried thereby, the type strips having type faces located adjacent the type faces of the type bars that are in printing position, whereby to print data on the coupons adjacent the data printed by the type bars, and impression making means co-operating with the type 40 faces to make impressions thereof on two rows of coupons at one operation.

5. In printing mechanism, the combination of settable slidably mounted type bars, having type faces that print in one plane, auxiliary printing 50 means located directly thereabove and having type faces that print in a higher plane, and impression making means co-operating with type faces of the type bars and auxiliary printing means to make impressions thereof in one opera- 55 tion.

6. In printing mechanism, the combination of settable slidably mounted type bars, having type faces that print in one plane, auxiliary printing 60 means located directly thereabove and having type faces that print in a higher plane, and impression making means having rollers co-operating with type faces of the type bars and auxiliary printing means to make impressions there- 65 of in one operation.

7. In printing mechanism, the combination of settable type bars having type faces thereon, auxiliary printing means removably supported in a plane above the type bars in close proximity 70 thereto whereby the type bars may move underneath the auxiliary printing means, the latter having type faces thereon located slightly above the plane of the type faces on the type bars, and impression making means co-operating with the 75

type bars and auxiliary printing means to make impressions in one operation.

8. In printing mechanism, the combination of settable printing means having type faces thereon, auxiliary printing means removably supported in a plane above and in close proximity to said first mentioned printing means, whereby the settable printing means may be adjusted underneath the auxiliary printing means, said auxiliary printing means having removable and replaceable interchangeable type strips provided with type faces, and impression making means co-operating with said settable and said auxiliary printing means to make impressions in one operation.

9. In printing mechanism, the combination of slidably mounted type bars, each having two series of type characters on its upper face, one series at each end, selected type characters of each series being capable of printing in two spaced lines, means for adjusting selected type bars to printing position, auxiliary printing means having a removable and replaceable printing slide, having two series of type characters thereon disposed adjacent the printing positions of the type bars, said slide being located in a plane above the type bars but in close proximity thereto,

whereby the type bars may be adjusted underneath the same and impression making means cooperating with the type bars and slide to make impressions therefrom in one operation.

10. In printing mechanism, the combination of settable slidably mounted type bars, having type faces that print in one plane, removable and replaceable, interchangeable auxiliary printing means located in a plane above the type bars, and impression making means cooperating with the type bars and auxiliary printing means to make impressions thereof in one operation.

11. In printing mechanism, the combination of settable slidably mounted type bars, having type faces that print in one plane, auxiliary printing means located in a plane above the type bars, and impression making means having rollers cooperating with the type bars and the auxiliary printing means to make impressions thereof in one operation.

12. In printing mechanism, the combination of printing elements arranged to print in two planes, and impression making means having rollers disposed at two fixed levels whereby to cooperate with the printing elements to make impressions therefrom in one operation.

MORRIS J. HOFFMAN.
